UNITED STATES PATENT OFFICE.

BERNHARD BISCHOF, OF WINTERTHUR, SWITZERLAND, ASSIGNOR TO SWISS LOCOMOTIVE AND MACHINE WORKS, OF WINTERTHUR, SWITZERLAND, A CORPORATION OF SWITZERLAND.

COMPRESSOR.

Application filed October 21, 1927, Serial No. 227,823, and in Germany November 1, 1926.

This invention relates to a compound arrangement for compressors of the multi-stage type.

In cell-compressors for high pressures, such as are necessary in refrigerating machines, compression must be effected in more than one stage. For this purpose two or more casings are mounted one behind another on a base plate common to them all, and their shafts are connected together by elastic couplings. The latter are necessary because it is difficult to arrange the individual rotors exactly coaxially. This necessitates however that each shaft extending out of its casing shall be packed by a stuffing box. The more stuffing-boxes are necessary, particularly in refrigerating machines, the more loss and defects in working may occur, particularly when high gas pressures are dealt with.

This invention has for its main object to obviate this defect.

To this end, there is connected between each two casings situated one behind another an intermediate member which encloses the elastic coupling and shuts it off from the atmosphere. If the intermediate member is also to equalize inequalities in the erection of the two casings, and to take care of varying expansion due to changes of temperature, its shape must admit of deformation within certain limits. The invention enables two stages of a compressor which are connected by such an intermediate member to be erected much more simply and at a lower cost than in any other manner.

Two embodiments of the invention are illustrated diagrammatically and by way of example in the accompanying drawings, 40 wherein:—

Figure 1 is an elevation, partly in section, showing a rigid intermediate member bolted to two adjacent stages, and

Figure 2 is a like view showing an elastic intermediate member bolted to two adjacent stages or cells.

Like reference numerals designate like parts in both views.

Referring first to Figure 1, the intermediate member aforesaid is in the form of a cylinder 1 having at its ends flanges 5, 5 bolted to the stages or cells 6 and 7 to be connected. Any gas that escapes through stuffing-boxes

provided in the end covers 2, 2 will collect in the cylindrical intermediate member 1 and are led through a tubular branch connection 3 to the inlet of the low pressure stage 6. An elastic coupling is provided within the cylinder 1 between the shafts of the rotors of stage 6 and stage 7.

Figure 2 shows a tubular intermediate member 4 bolted by flanges 5 to the end cover plates 2 of the stages 6 and 7. The shape, material and wall-thickness of this member 4 are so selected that the member particularly can accommodate expansion due to heat. In this construction also it is preferable to lead gas that leaks from the two stages 6, 7 through the stuffing-boxes, to the suction pipe of the low pressure stage of the compressor by way of a branch pipe 3 that opens into the tubular intermediate member 4.

I claim:—

1. In a multi-stage compressor, the combination with two casings constituting each a stage arranged end to end and having each a rotor, and a coupling connecting the rotors, of an intermediate member enclosing from the atmosphere the space between the ends 80 of the casings containing said coupling.

2. In a multi-stage compressor, the combination with two stages operatively connected end to end, of a tubular intermediate member which shuts off from the atmosphere 85 the space between the adjacent ends of the stages.

3. In a multi-stage compressor, the combination with two stages operatively connected together end to end, of an elastic tubular intermediate member which is connected air-tight to said stages and shuts off from the atmosphere the space between the adjacent ends of the said stages.

4. In a compressor of the character described, the combination with two cells operatively connected together end to end, of an intermediate member that is connected air-tight to said cells and shuts off from the atmosphere the space between the adjacent 100 ends of said cells, which intermediate member has an aperture for connection with the suction side of the low-pressure cell.

In testimony whereof I affix my signature.

BERNHARD BISCHOF.
